his Attorney

UNITED STATES PATENT OFFICE.

BENJAMIN H. LEVIN, OF CHICAGO, ILLINOIS.

LOCK.

Application filed March 31, 1923. Serial No. 629,009.

To all whom it may concern:

Be it known that I, BENJAMIN H. LEVIN, a citizen of the United States, and a resident of the city of Chicago, county of Cook, and State of Illinois, have invented certain new and useful Improvements in Locks, of which the following is a specification.

My invention relates to improvements in locks and more particularly to spring locks adapted for use on canteen bags, suit cases, and the like, and has for an object to make such a lock in which the bolt operating mechanism is housed in a small casing on top of the lock and only the locking bolt is mounted beneath the top plate of the lock within the confines of the depending flanges of the lock, so that no portion on the under side of the lock protrudes or needs to be set into the bag or case.

Another object is to make the eye portion of the hasp device integral with the hasp plate or strap, instead of riveting said eye portion on said hasp plate as in the usual types of construction.

Another object is to provide an inexpensive, durable and efficient lock of this kind.

Other objects will appear hereinafter.

The invention consists in the combinations and arrangements of parts hereinafter described and claimed.

The invention will be best understood by reference to the accompanying drawings forming a part of this specification, and in which,

Fig. 1 is a plan view of my lock mounted in position on a canteen bag a portion of which is shown;

Fig. 2 is an inverted view of the lock;

Fig. 3 is a cross section taken on line 3-3 of Fig. 1;

Fig. 4 is an enlarged, inverted partial view of the lock with the locking bolt removed;

Fig. 5 is an enlarged sectional view on line 5-5 of Fig. 4, and

Fig. 6 is a view of the key.

In the drawings, 10 represents a portion of a canteen bag or suit case to which the main portion 11 of my improved lock is fastened, as by means of rivets 12 or the like. The lock also includes the hasp device hav-

ing an attaching plate 13 mounted on the cover 14 of the bag 10, as by means of rivets 15 or the like.

The main portion 11 of the lock comprises a top plate 16 with flanges 17 extending at right angles from the edges of said plate, thus substantially forming a housing. Lugs 18 are turned inward from the lower edges of the flanges 17 for retaining and guiding the locking plate or locking bolt 19 between said flanges, and a spring 20 has the end 20' of one arm engaging in an opening in the plate 19 and the end of the other arm held by a lug 21 on the flange 17, said spring automatically holds said bolt in locking position. Said locking bolt and spring are thus entirely contained or housed between flanges 17 and no part of the lock protrudes beneath the lower edges of said flanges, but the flanges are seated directly on the canteen bag and no opening need be provided on the bag for any protruding part of said lock.

A small casing 22 is mounted on the top plate 16 of the lock by means of a pair of integral fingers 23 which extend through and slide in enlarged slots 24 provided in the top plate 16, and pass through close fitting slots 25 in the locking bolt 19, the ends of said fingers being bent over against the lower side of said bolt 19.

The mechanism for operating the locking bolt is housed in said casing 22 and includes a circular disc 26 having a smaller circular portion 27 which extends partly between fingers 23. A pin 28 extends from said portion 27 and operates in an irregular slot 29 provided in the top plate 16, said slot having a laterally extending narrow portion for receiving said pin to hold the plate 19 in locking position, and a longitudinally extending portion 29' which is parallel with the slots 24 and in which said pin moves while the fingers 23 move longitudinally in the elongated slots 24 in plate 16 when the locking plate 19 is slid longitudinally into locking and unlocking position. A pin 30 is provided on the upper face of the disc 26 and extends into the casing 22 to be engaged by the web 31 of the key 32. The key is inserted through the key hole 33 in the casing 22, and the lower end or pin 34 of the key stem engages in the opening 35 in the disc

26 and in the opening 36 in the locking bolt 19, and moves longitudinally through the elongated slot 37 in the top plate 16, while said key carries with it the casing 22, as the 5 locking bolt 19 is being operated. A coil spring 38 holds the disc firmly in set position and also resiliently to permit said disc to move slightly upward to free the side notch 39 of the disc from the bent portion 10 of the finger 23, in order to move the device out of the released position into the illustrated locked position.

The hasp device which has its attaching plate 13 fastened to the covering 14 of the 15 bag, comprises a hasp plate or strap 40 pivotally mounted on said attaching plate by means of a rivet 41 passing through ears 13' and 40' provided on said attaching plate and said strap portion, respectively. A coil 20 spring 42 normally moves and retains the strap 40 in released position. The lock engaging eye portion 43 of the hasp device is made integral with the movable strap 40 and is bent back upon the part 40 and then bent 25 downwardly to form a ledge or flange 44 for covering the slot 45 in the top plate 16, through which slot the eye portion 43 extends, and receives the locking tongue 46 on the bolt 19 to hold said hasp in locked position.

30 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 35 the appended claims.

40 Having described my invention what I claim as new and desire to secure by Letters Patent, is:

1. A lock comprising a top plate with 45 downwardly extending flanges, a locking member mounted between said flanges, a casing movably mounted on said plate, means on said casing and extending through said plate for engaging and operating said locking member, and a key operated member mounted in said casing and having means movable in one part of a slot in said plate to hold said locking member locked and movable in another part of said slot to permit release movement thereof.

55 2. A lock of the class described comprising a top plate with downwardly extending flanges, a locking member mounted between said flanges and retained therein by inwardly bent lugs at the lower edge of said flanges, a spring having one arm held by a lug on said flange and having another arm engaging in an opening in said locking member to normally move said member into 60 locking position, and a casing on said top

plate with means movable in an opening in said plate to lock said member in position.

3. A lock comprising a housing with a top plate, a locking member mounted in said housing, a casing movably mounted on said plate, means on said casing for engaging and operating said locking member, and a key actuated member mounted in said casing above said plate and having integral means mounted to move in a slot in said plate to either hold said casing and locking member locked or to permit release movement thereof.

4. A lock comprising a housing having a top plate with an irregular slot, a locking member mounted in said housing, a casing slidably mounted on said plate, means extending from said casing through elongated slots in said plate and engaging said locking member, a key actuated member mounted in said casing, and a pin on the last said member movable in an elongated part of said irregular slot to permit movement of said locking member, said pin being movable into another part of said irregular slot to hold said casing and locking member in locked position.

5. A lock comprising a housing having a top plate with an irregular slot, a locking member mounted in said housing, a casing movable on said plate, fingers extending from said casing slidable through slots in said plate and fastened to said locking member, a disc mounted in said casing, means mounted on said disc for engagement by a key, and a pin extending from said disc into said irregular slot, said pin being movable into an elongated part of this slot to retain the parts in locked position.

6. A lock comprising a top plate with 105 downwardly extending flanges, a locking member mounted between said flanges, a casing slidably mounted on said plate, fingers extending from said casing through slots in said plate and engaging said locking member for moving the same, a disc mounted for vertical and rotational movement in said casing and having means for engagement by a key, means on the lower side of said disc movable in an irregular slot in said plate, and a spring mounted in said casing and bearing against said disc to retain said disc firmly seated in position.

110 7. A lock comprising a top plate having downwardly extending flanges, a locking member mounted within the confines of said flanges, lugs extending inwardly from the lower edge of said flanges beneath said locking member, a casing mounted on said plate, fingers extending from said casing through elongated slots in said plate and being fastened to said locking member, a disc mounted in said casing and having means for engagement by a key, and a pin on the lower side of said disc movable in an irregular 115 120 125 130

slot provided in said plate, said pin being movable into a narrow part of said irregular slot to lock said locking member in position and being movable into an elongated 5 part of said slot to permit said locking member and casing to move with respect to said plate.

8. A lock comprising a top plate with a slot and with downwardly extending 10 flanges, a locking member mounted within the confines of said flanges, a tongue on said member which is movable across said slot, a hasp device having a movable strap with an integral portion bent back upon said 15 strap and then downward to pass through said slot and be held by said tongue, a casing with elements slideable in slots in said top plate and fastened to said locking member, key engaged means in said casing, and 20 a pin on said means movable in an irregular slot in said top plate to either hold said

casing and locking member locked or permit release movement thereof.

9. A lock comprising a top plate having downwardly extending flanges, a locking 25 member mounted between said flanges, a casing slidably mounted on said top plate, fingers extending from said casing through slots in said plate and engaging said locking member for moving the same, a notched 30 disc mounted for vertical and rotational movement in said casing and having means for engagement by a key, means on said disc movable in a slot in said plate to retain the parts in locked position or permit release 35 movement thereof, and a spring mounted in said casing to engage the disc and hold its notch against one of said fingers and retain said disc firmly seated in position.

In testimony whereof I have signed my 40 name to this specification.

BENJ. H. LEVIN.
